181,007

COVER FOR SAUCE PAN OR OTHER KITCHEN UTENSIL

Richard F. Krause, Massillon, Ohio, assignor to The Enterprise Aluminum Company, Massillon, Ohio, a corporation of Ohio

Application December 13, 1956, Serial No. 44,181

Term of patent 7 years

(Cl. D44—1)

Fig. 1

Fig. 3

Fig. 1 is a top plan view of a cover for sauce pan or other kitchen utensil, showing my new design;

Fig. 2 is a side elevation of the same; and

Fig. 3 is a fragmentary sectional view taken substantially on the line 3—3, Fig. 1.

I claim:

The ornamental design for a cover for sauce pan or other kitchen utensil, substantially as shown.
